UNITED STATES PATENT OFFICE

FRANK M. ROBY, OF CLEVELAND, OHIO

CONDITION INDICATOR FOR LOW-WATER ALARMS

Application filed October 21, 1927. Serial No. 227,759.

This invention relates to low water alarms for boilers and more particularly to means for indicating the operative condition of the alarm.

Low water alarms, particularly those of the float type are usually so constructed that they will actuate an alarm indicating member by steam pressure whenever the water level in the boiler drops below a predetermined point. Accordingly, when a boiler is being blown down and drained in the roundhouse the alarm is actuated for a comparatively long period of time before the pressure drops to a point where it is not high enough to sound the alarm. The continual operation of the alarm is an annoyance to the attendants and the natural tendency therefore is to remove or to muffle the alarm whistle. So far as I am aware, no valve has been provided for controlling the flow of steam to the alarm member, for the reason that there is danger of such valve being closed without any one detecting the condition of the valve when the boiler is again placed in service.

The principal object of the present invention is to provide means for enabling the steam supply to be shut off while the boiler is being blown down and drained, and which will preclude the possibility of again starting the boiler without opening the valve.

I accomplish this object by using preferably a three-way valve having one inlet and two outlets. The inlet is connected to the source of steam supply. One of the outlets is connected to the alarm and the other outlet leads to the atmosphere. The two outlets are disposed opposite each other and the valve head is arranged to move between the openings, so as to open one when the other is closed. Thus, if the connection to the alarm should be closed, steam will be allowed to escape to the atmosphere where it will be at once detected by an inspector. When the atmospheric opening is closed the connection to the alarm will have been opened.

A preferred means for carrying out my invention is illustrated in the drawings in connection with a low water alarm, which is shown in end elevation in Fig. 1; Fig. 2 is a plan view of the alarm, and Fig. 3 is a lon-

gitudinal vertical section through the valve.

In the drawings, 10 indicates a boiler to which a low water alarm of the float type may be attached. One type of such alarm is mounted within a casing 11 and has a float 55 actuated valve which is arranged to operate an alarm member such as a whistle 12. The passage of steam to the whistle is controlled by the rise and fall of water in the float chamber.

The steam for actuating the whistle may be taken from the steam space in the boiler and may flow through connection 15, conduit 16, hand operated valve 17, and conduit 18, from whence it may enter the valve chamber 65 which is indicated in general at 19. Details of construction of such float and valve chamber as well as the manner in which an alarm of this type may be operated is illustrated and described in my co-pending application, 70 Serial No. 227,760, filed October 21, 1927, for a low water alarm.

To obviate the possibility of operating the boiler with the alarm valve closed, I employ a three-way valve indicated in general at 17. 75 Such valve has an inlet passageway 20 and two outlet passageways indicated at 21 and 22 respectively. The ports leading to such outlet passageways are disposed opposite each other, while a valve head is arranged between 80 the ports and is adapted to open one before the other is closed. Such valve head is shown at 25 as being attached to a stem 26, which in turn is threaded at 27 to engage a correspondingly threaded portion 28 in the valve housing. 85 A handle 29 attached to the stem functions to permit operation of the valve head.

The passageway 21 communicates with conduit 18, which in turn leads to the alarm while the passageway 22 leads to the atmosphere. 90 To prevent the atmospheric passageway from being stopped-up by an attendant, I have illustrated such passageway as leading into an extension 30, which has a plurality of small openings 31 leading therefrom. The extension may be integral with a threaded member 32, which functions as a cap for the end of the valve housing, and also carries the seat for shutting off the steam to the atmosphere.

With the alarm illustrated and described, 100

it is obvious that under normal conditions the valve head will be in the position shown in Fig. 3. Under such conditions the steam will have direct communication with the conduit 18 and will be prevented from escaping to the atmosphere. At infrequent intervals the valve head will be withdrawn to close the passageway 21 and to open the passageway 22. At such times any steam in the boiler 10 will escape to the atmosphere in such large quantities as to be noticeable to the inspector or engineer. Thus there would be no danger of the boiler being operated with the valve in the wrong position.

15 I claim:

1. The combination with a boiler, of a low water alarm indicating member associated therewith, said boiler having an atmospheric discharge opening independently of the 20 alarm indicating member, and manually operable means for controlling the flow of steam to said member and to said discharge opening respectively, said means being arranged to permit the flow of steam to the atmosphere when the flow of steam to said member is shut off.

2. The combination with a boiler, of a steam conduit leading therefrom, an alarm indicating member connected to the conduit, 30 an atmospheric bleed also connected to the conduit, valve means including a single manually operable member associated with the conduit for directing the flow of steam from the source of supply either to the alarm indicating member or to said bleed.

3. In combination, a boiler, a low water alarm indicating member associated therewith, a steam connection between the boiler and said member, a valve in said connection, 40 said valve being adapted to direct the flow of steam from the boiler either to the atmosphere or to said member, each action being to the exclusion of the other.

4. In combination, a boiler, a low water alarm indicating member associated therewith, a steam connection between the boiler and member, means associated with said connection for directing steam to the member or to the atmosphere, each to the exclusion of the 50 other, said means being operable to effect substantially simultaneous change of direction in steam flow.

5. The combination with a low water alarm indicating member, of a source of steam supply for actuating the member, a conduit leading from said source of supply to the member, a valve in said conduit, said valve having one inlet and a plurality of outlets independent, the inlet being in communication 60 with the source of supply, one of the outlets being in communication with the member and the other outlet being in communication with the atmosphere, and means associated with the valve for closing one outlet and opening 65 the other.

6. The combination, with a low water alarm indicating member and a source of steam supply for actuating said member, of a conduit leading from said source of steam supply, and a three-way valve having its inlet connected with said conduit and one of its outlets connected with said indicating member and the other outlet with the atmosphere, the atmosphere outlet permitting the escape of steam from the boiler without actuating the alarm indicating member, said outlets having two opposed seats in the valve and the operating member of the valve having a suitable head which in one direction its movement coacts on one side with one seat and in the other direction of movement coacts on the other side with the other seat.

7. The combination with a low water alarm and a steam boiler, of a conduit from the boiler, a valve casing having an inlet connected with the conduit and two outlets extending in opposite directions, one connected with the low water alarm and the other with the atmosphere, said outlets terminating in opposed seats, a movable valve plug between said seats adapted on one side to engage one seat and on the other side to engage the other seat, and a rotary stem on which said plug is mounted, said stem having a threaded connection with the valve casing whereby rotation of the stem may change the presentation of the valve plug from one seat to the other.

In testimony whereof, I hereunto affix my signature.

FRANK M. ROBY.
